UNITED STATES PATENT OFFICE.

EDGAR HOMER KENDALL, OF ALLIANCE, OHIO, ASSIGNOR TO THE ALLIANCE MACHINE COMPANY, OF ALLIANCE, OHIO, A CORPORATION OF OHIO.

CRANE.

Application filed February 13, 1926. Serial No. 88,030.

The present invention relates broadly to raising and lowering mechanism, and more particularly to cranes for this purpose embodying intergeared and separately driven drums.

It has heretofore been proposed in the art to which the present invention relates, to operate each of two permanently intergeared drums by means of separate motors, as disclosed for example, in my prior Patent 1,148,323 of July 27, 1915. Obviously, it is essential that the two drums operate at the same speed, and this requirement has presented a very considerable difficulty, by reason of inability to insure the running of one motor at the same speed as the other, or the failure of the brakes or the motors or both to operate equally or simultaneously. If the motors should not operate synchronously, it is apparent that there will be a tendency for the gearing of one of the drums to crawl upon the gearing of the other drum, thereby tending to raise the first drum bodily. This has frequently produced such a strain on the journals and mountings that either the mountings have been broken loose, or the journals or gearing injured.

Efforts have been made to obviate difficulties of the nature referred to by the utilization of suitable types of slip gears as part of the driving connections of the respective motors, thereby permitting one motor to overrun the other in the event of unequal or non-simultaneous brake application. Such constructions have been extremely desirable from the standpoint of eliminating part of the difficulties previously encountered, but they have required a nonpositive driving connection which in some cases is objectionable, and the cost of the installation has been increased, without obtaining synchronism of the driving motors with uniformity of brake application on both of the motors and drums.

The present invention has for one of its objects the provision of a crane structure in which difficulties of operation by reason of lack of synchronism or uniformity in motor or brake application are obviated by mechanically connecting the motors themselves to insure uniformity and synchronism of the driving and controlling means for the two drums.

In the accompanying drawings there is shown for purposes of illustration only, a preferred embodiment of my invention, it being understood that the drawings do not de-

fine the limits of my invention as changes in the construction and operation disclosed therein may be made without departing from the spirit of my invention or scope of my broader claims.

60

In the drawings:

Figure 1 is a top plan view of one form of crane trolley embodying the present invention, and

Figure 2 is an end elevation, partly broken away, of the construction shown in Figure 1.

In carrying out the present invention there may be provided a trolley frame 2 supported on track wheels 3 which run on tracks 4 of a traveling crane bridge.

70

Journaled in suitable bearings 5 on the trolley frame, are two hoisting drums 6 placed side by side. Rigidly secured to each of the drums is a driving gear 7, these two gears directly intermeshing as clearly illustrated in the drawings. For rotating the drums there are provided motors 8 preferably located in alignment on opposite sides of the trolley frame, and having their armatures directly and mechanically connected by a common shaft 9, herein illustrated as comprising the driving shaft. The motors are preferably of similar construction, and each is provided with a brake 10 which may be of the magnetic type as well understood in the art.

75

Adjacent each of the motors the trolley frame carries a housing 11 in each of which is journaled one end of an intermediate shaft 12 extending parallel to the drums. Within the housings each of the intermediate shafts carries a worm wheel 13 both in driven relationship to worms 14 on the driving shaft 9. At their opposite ends the intermediate shafts have secured thereto gears 15 meshing with the large gears 7 on the drums.

95

With the construction described, it will be apparent to those skilled in the art that the motors are compelled to operate in synchronism due to the direct mechanical connection between their armatures. Even in the event one motor should become defective, the other motor may drive the shaft 9, and through it both of the drums 6 without any tendency of the drums to crawl one on the other. In like manner, the two brakes 10 exert their combined influence on the shaft 9, so that unequal wear on the brakes or failure of the same to operate simultaneously will not effect the uniformity of brak-

100

105

110

ing on the respective drums, since both are acted upon uniformly and simultaneously at all times both during driving and braking by the same shaft. This shaft therefore 5 constitutes a common driving and braking means for intergeared drums having separate driving and controlling means, thereby insuring the desired synchronous operation thereof and constituting one of the advantages of the present invention.

A further advantage of the invention arises from the use of worm gearing for driving the drums. This type of gearing not only readily provides any desired gear reduction with 15 a powerful drive, but by properly designing the teeth can be made effective for preventing accidental or undesired retrograde rotation of the drums. Thus, in the event of failure of both of the motors and brakes, 20 the crane may effectively hold its load against dropping.

I claim:

1. A crane structure comprising a pair of drums each having a gear secured thereto, the 25 drums being connected through said gears, a pinion shaft for each of the drums, said shafts having a gear connection with the drum gears, a drive shaft, a worm gear connection between the drive shaft and each of the pinion shafts, 30 a motor adjacent each of the worm gear connections, the armature of each motor being mounted on the drive shaft, and brake means for each motor.

2. A crane structure comprising a pair of 35 drums each having a gear secured thereto, the gears meshing with one another, a drive shaft extending substantially perpendicular to the drum shafts, a connection including worm gearing between the drive shaft and 40 each of the drums, a driving motor adjacent each of the worm gear connections and brake means for the drive shaft adjacent each of the motors.

3. A crane structure comprising a pair of 45 drums each having a gear, the gears meshing with one another, a drive shaft extending at an angle to the drum axes, connections be-

tween the drive shaft and each of the drums, each of said connections including worm gearing, and a driving motor adjacent each 50 of the worm gear connections, a gear on one drum meshing with a gear on the other drum.

4. A crane structure comprising a pair of drums each having a gear, the gears meshing with one another, a drive shaft extending at 55 an angle to the drum axes, two motors, one for each drum, having their armatures mounted on the drive shaft, and connections from the drive shaft to each of the drums, each connection including worm gearing adjacent a 60 motor, a gear on one drum meshing with a gear on the other drum.

5. A crane structure comprising a pair of drums each having a gear, the gears meshing with one another, an intermediate shaft for 65 each drum, each intermediate shaft having a pinion meshing with its drum gear, a worm gear on each intermediate shaft, and a common worm shaft making a direct connection with each of said worm gears.

6. A crane structure comprising a pair of drums each having a gear, the gears meshing with one another, an intermediate shaft for each drum having a pinion meshing with the drum gear, a worm gear on each intermediate shaft, a shaft extending transversely 75 of the intermediate shafts and carrying worms meshing with the worm gears, and a driving motor adjacent each of the worm gear connections.

7. A crane structure comprising a pair of drums making a direct gear connection with one another, intermediate shafts for the drums carrying pinions which make a gear connection with the drums, a worm gear on 85 each intermediate shaft, a worm shaft extending transversely of the intermediate shafts and carrying worms meshing with the worm gears, and a driving motor adjacent each of the worm gear connections.

In testimony whereof I have hereunto set my hand.

EDGAR HOMER KENDALL.
